UNITED STATES PATENT OFFICE.

JOSEPH W. GREGORY, OF SEAT PLEASANT, MARYLAND.

BILL-FILING DEVICE.

1,208,954.

Specification of Letters Patent. Patented Dec. 19, 1916.

Application filed March 28, 1916. Serial No. 87,229.

To all whom it may concern:

Be it known that I, JOSEPH W. GREGORY, a citizen of the United States, residing at Seat Pleasant, in the county of Prince 5 Georges and State of Maryland, have invented certain new and useful Improvements in Bill-Filing Devices, of which the following is a specification.

This invention is an improvement on the 10 support for paper files shown in the patent issued to me July 28, 1914, No. 1,105,421.

The object of this invention is to simplify and cheapen the device, and especially to adapt it to receive a specially constructed 15 needle. The commercial value of an article of this character, especially when it is to be used as an advertising novelty, depends to a great extent on the cost of manufacture, and it is therefore essential that all parts 20 be so designed that they can be made by machinery, and require no hand finishing.

The present invention also consists in the 25 novel features of construction hereinafter described, pointed out in the claims, and shown in the accompanying drawings, in which:—

Figure 1 is a vertical section, illustrating the device in position for use. Fig. 2 is a 30 top plan view of the bracket. Fig. 3 is a face view of the bracket. Fig. 4 is a perspective view of the needle. Fig. 5 is a plan view of a modification. Fig. 6, is a side elevation of the modified form, with the needle in position.

In constructing the device I employ a flat 35 plate forming a wall bracket 1, preferably of metal and adapted to be secured to any vertical surface. This bracket has a forwardly projecting arm 2 the forward end portion of which is bent upwardly and rearwardly, the free extremity being curved upwardly as at 3. The arm has a longitudinal slot 4, extending nearly to the wall portion in the lower part of the arm, and 40 terminating in the upper part, adjacent the end portion 3, in an elliptical enlargement 5.

A cylindrical needle 6 is pointed at one 45 end and the opposite end portion is flattened as at 7, and provided with an eye 8. In the eye is secured a thread 9, of cord, twine or thin wire, carrying at its free end a button or stop 10.

The flattened portion merges or tapers 50 into the cylindrical portion as shown at 7a. 55 In Figs. 5 and 6 I have shown a slight

modification, in which the device is adapted to be secured to a flat surface, as the edge of a desk, table or counter. This comprises a plate 11 having an arm or tongue 12, and the plate has flanges 13 on opposite sides of 60 the tongue to engage an edge of the desk or table. This arm is bent upwardly and rearwardly as shown at 14 and is slotted as at 15, the upper end of the slot terminating in a circular opening 15a.

The arm 2 is provided with an opening 16 adapted to receive the needle and a similar opening 16a is formed in the tongue 12. The bracket 1 has a fastener-securing opening 17, and the plate 11 a similar opening. 70

In use current bills or papers are designed to be placed on the needle, the needle occupying a position in the device as shown in Figs. 1 and 5, according to the form of needle support employed. Then when such bills or papers are to be filed, the needle is lifted from position and the bills or papers slipped down the needle on to the thread 9 as shown in Fig. 1. The needle is then replaced in position.

In placing the needle in the bracket 1 it is held in a vertical position, the flattened portion passed into the slot 4 and moved downwardly and then released. On downward movement the upper part of the needle 85 is tilted forward, the cylindrical portion passing into the elliptical opening 5 and the tapering portion, at 7a engaging the lower inner portion of the slot. Owing to the shape of the opening 5 the needle moves 90 freely and easily in a vertical position but as it shifts into the slanting position shown, with the lower end engaging the vertical surface to which the bracket is secured, it fills said opening 5 and at the same time 95 becomes wedged in the lower portion of the slot. The needle therefore becomes practically automatically locked in position, and bills and papers can be readily forced on it without in any way disturbing its 100 position.

To remove the needle it is only necessary to push it upwardly to disengage the tapered portion 7a and swing into a vertical position to relieve binding action at the opening 5, 105 and the portion 7 can then be lifted into a position from which the needle can be bodily moved in a horizontal plane from the slot 4.

In the form shown in Fig. 6 the needle occupies a vertical position, the tapered por- 110

tion wedging in the lower portion of the slot and the cylindrical portion of the needle resting in the circular opening 15^a.

When not in use, or if the device is placed 5 in a position where it is not desirable for the point to project the needle can be inverted and dropped into either the opening 16 or 16^a.

What I claim is:—

10 1. The combination with a bracket having a forwardly extending and upwardly bent, longitudinally slotted arm, of a needle having a cylindrical portion and a flattened portion gradually merging into said cylindrical 15 portion, and adapted to pass into and be automatically locked in said slot, and article receiving means carried by said needle.

20 2. A device of the kind described comprising a bracket adapted to be secured to a flat surface, and having a forwardly projecting arm, said arm curving upwardly and rearwardly, and being longitudinally slotted, the upper end of the slot terminating near the free end of the arm in an enlargement, 25 and a needle having a cylindrical portion adapted to rest in said enlargement and a flattened portion adapted to pass into said slot, and to wedge in the lower portion of the slot at the point of merger of the flattened and cylindrical portions of the needle.

30 3. A device of the kind described comprising a bracket, an arm carried thereby, said arm extending forwardly and then bent upwardly and back upon itself, the arm 35 having a longitudinal slot extending from the lower to the upper portion of said arm, and terminating in the upper portion in an enlargement, and a thread supporting needle

having a flattened portion adapted to be passed in a vertical position into said slot, 40 and a cylindrical portion adapted to descend into said enlargement, as and for the purpose set forth.

45 4. A device of the kind described comprising a wall bracket, an arm carried thereby said arm being bent upwardly and rearwardly, the bent portion being longitudinally slotted, said slot terminating in its upper portion in an elliptical opening, and terminating in its lower portion to the rear 50 of and below said opening, and a thread supporting member having a flattened and a cylindrical portion, said portions merging slopingly into each other, said flattened portion being adapted to pass into the upper and lower portions of said slot with said member in a vertical position, the member being adapted to move downwardly into an inclined position the merging portions of the member engaging the rear lower portion 55 of the slot and the cylindrical portion resting and binding in the elliptical portion.

60 5. A device of the kind described comprising a curved arm bent on itself, and having a longitudinal slot, portions of said slot 65 being in vertical alinement, the upper portion terminating in an enlargement, and a paper supporting member having a flattened portion adapted to be passed simultaneously into both portions of the slot and to move 70 longitudinally in said slot thereby bringing the cylindrical portion of the member into said enlargement and into engagement with the lower portion of the slot.

In testimony whereof I affix my signature. 75
JOSEPH W. GREGORY.
